ATTORNEY

UNITED STATES PATENT OFFICE.

ANTON J. WOSTRCHILL, OF VALPARAISO, NEBRASKA, ASSIGNOR OF ONE-THIRD TO FERDINAND J. POTTER AND ONE-THIRD TO CHARLES M. TAYLOR, OF VALPARAISO, NEBRASKA.

WRENCH.

Application filed May 23, 1923. Serial No. 640,959.

The object of this invention is to produce a tool in the nature of a wrench for use by automobile mechanics which shall be of a construction to permit of the device being operated to unscrew nuts from bolts in places where the same are not readily accessible to engagement by an ordinary wrench.

To the attainment of the foregoing and other objects which will present themselves as the nature of the invention is better understood, reference is to be had to the drawing which accompanies and which forms part of this application.

In the drawing:—

Figure 1 is a view illustrating the arrangement of the tool for removing the nuts from bolts on the crank case of an automobile.

Figure 2 is an enlarged view of the tool.

Figure 3 is a sectional view on the line 3—3 of Figure 2.

Figure 4 is a sectional view on the line 4—4 of Figure 2.

In carrying out my invention, I provide a straight shank 1 with an offset portion adjacent one of its ends providing the shank with a rightangular handle 2. The shank outward of the handle has swiveled thereon a head 3. The shank has its opposite end bent to provide a U-shaped extension disposed in the direction of the handle 2 but of a length less than that of the handle. The arm 4 of the extension is disposed nearest the handle 2, the outer arm 5 having its extremity enlarged and bifurcated and being provided with a transverse opening to receive therethrough the shank of a socket 6. On the shank, on the portion thereof received in the bifurcated end of the arm 5 there is a toothed wheel 7 designed to have the teeth on either of its faces engaged by oppositely arranged spring influenced dogs 8, the said dogs having their tail portions engageable by cam surfaces on a milled sleeve 9 that surrounds the bifurcated end of the arm 5. The sleeve is limited in turning by the contacting engagement of a pin 10 with the opposed walls

or shoulders formed by notching the inner edge of the sleeve. When the sleeve is turned to one position, one of the dogs will engage 50 the wheel 7 to turn the socket 6 in one direction with the turning of the handle 2, and when turned to an opposite direction the second dog will engage the wheel to turn the socket in an opposite direction. When the 55 notch in the shank is arranged centrally of the pin 10 the springs that influence both of the dogs 9 brings both of the dogs into engagement with the ratchet wheel so that the socket is locked to the device. 60

In Figure 12 I have illustrated one manner in which the wrench can be conveniently used. It will be noted that the sweep provided by the U-shaped extension at one end of the shank 1 will evade the edge of the 65 engine crank case during the tightening or loosening of the nuts thereon, while the space between the arm 4 and the handle 2 permits of the wrench turning without contacting the radius bars of the machine. The wrench is, of course, susceptible to other uses in connection with an automobile and like mechanisms, but it is thought that the foregoing description when taken in connection with the drawing will amply set forth the construction and advantages of the improvement. 70

Having described the invention, I claim:—

In a tool for the purpose set forth, a straight shank having a head swiveled to one end thereof, a rightangular handle formed therewith inward of the head and its second end formed with a U-bend extended in the same direction and arranged in the same plane as the handle, the outer arm of the 80 U-bend being enlarged and bifurcated, a 85 socket member in said bifurcated end and a ratchet mechanism associated with said socket member and the axial plane of the 90 socket being in a line with that of the shank.

In testimony whereof I affix my signature.

ANTON J. WOSTRCHILL.
